UNITED STATES PATENT OFFICE

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN

PUMP

Application filed July 23, 1928. Serial No. 294,912.

My invention relates to pneumatic pumps and more particularly to a method of and means for preventing frosting or freezing of the exhaust valve or adjacent parts while the pump is in operation.

Pneumatic pumps of the type disclosed in my prior Patent 1,658,032 of February 7th, 1928, are now employed in car washing systems and the like, that is, systems where air and water under high pressure are projected through a suitable nozzle for washing automobiles, etc. The air pressure employed is of the order of 100 to 150 lbs. gauge pressure, that is, approximately 7 to 10 atmospheres. This pressure prevails in both the nozzle and in the air pumping chamber and is required in order to get the necessary atomizing and scouring effect. The pump chamber may exhaust into atmosphere or into the intake of the compressor, but at all events the pressure drop is very considerable. Under the well-known relation between pressure volume and temperature as set out in the laws of Charles and of Boyle, pressure, volume and temperature are interrelated variables. This relation is familiarly expressed in the equation PV equals KT . Where P is pressure V is volume, and T is absolute temperature and K is a suitable constant. Hence a drop in pressure is accompanied by an increase in volume and, unless special provision is made to prevent the same, by a drop in temperature.

The point where the high pressure in the pumping chamber is released is the exhaust valve and its cooperating port. The rapid expansion of the air tends to lower the temperature of the exhaust valve, and where, as in car washing, the pump is called on to operate continuously for hours at a time at a high rate of water delivery, the exhaust valve and its surrounding valve seat become so chilled as to form frost or ice which finally interferes with the operation of the valve.

I have studied the difficulty and endeavored to find means for preventing interference with the exhaust valve by frosting. Any means for applying heat from usual heating means such as gas, electricity, steam or the like, or the employment of hot air would add

unbearable complications besides adding a possible danger to the operator and to the mechanism. Furthermore a great deal of heat would be required for continuous operation.

I have observed that water contains a relatively great amount of latent heat. Even if water is at freezing temperature, it will not freeze until it loses its latent heat of fusion. This means that the formation of frost can be prevented by a bath of water even if the same is but little above freezing. I have conceived the idea of washing the exhaust valve with some of the water employed in the pump chamber to prevent frosting or freezing. The water from the city main is usually around 40 to 50 degrees Fhr., and hence in addition to the latent heat of fusion, contains a very considerable quantity of heat at a temperature well above freezing.

I have, according to the present invention, provided means for periodically squirting a small amount of water onto the exhaust valve and its adjacent parts in order to defrost the valve or prevent the formation of frost or freezing at this point. In the preferred form of my invention I provide a small ejector for squirting a small amount of water onto the valve or its adjacent parts at each stroke of the pump. Preferably this squirt occurs during the outrush of air or during the latter part of the exhaust so that the squirt of water is caused to reach all the desired parts and to be carried out of the way of the exhaust valve and its port.

In this manner the bathing of the exhaust valve is graduated in accordance with the amount of air exhausted therethrough so that frosting is eliminated.

In the preferred form of the invention the water for bathing the exhaust valve is taken from the discharge connection, that is, on the remote side of the water discharge check valve, through the clearance of the discharge check valve stem so as to remove any sand or other impurities which might tend to become lodged in the clearance space about the stem. In many cases in pneumatic pumps sand or other impurities are carried with the water, particularly during the initial installation.

and this may become lodged either in the clearance space or beyond the stem of the discharge check valve. Such lodgment is avoided by the use of the present invention.

5 While I shall describe in connection with the accompanying drawings the specific form in which I prefer to embody my invention, it is to be understood that the invention is not to be limited to the specific means which I 10 have herein shown and described, and that in fact widely different means may be employed in the practice of the broader aspects of my invention.

In the drawings,

15 Fig. 1 is a side elevation considerably shortened with the lower part of the barrel and connected parts shown in section.

20 Fig. 2 is a vertical section through the head and the upper part of the pumping chamber.

25 Fig. 3 is a vertical section through the lower part of the pumping chamber, Figs. 2 and 3 when put in vertical alinement constituting a vertical section through the pump; and

30 Fig. 4 is a section through the discharge check valve box taken on the axis of the discharge check valve stem.

The pump in which I have shown my invention as embodied is of the type originally disclosed and claimed in my prior Patents No. 1,658,031 and 1,658,032, both granted February 7th, 1928, to which reference is here made for a full disclosure of the construction and mode of operation of the parts.

35 The pump herein shown comprises the head member 1 mounted on top of a barrel 2 providing a chamber 3, which is known as the pumping chamber. The barrel 2 is closed by a foot member 4, which contains the intake 40 connection for liquid to be pumped. The head and foot members are tied together by a tension connection, which includes the discharge pipe 5 threaded into a socket in the lower part of the head member 1, a valve box 45 6 into the upper end of which the discharge pipe 5 is threaded, and a stud 7 which passes through the foot member 4 and is held by a cap nut 8 threaded upon the free end of the stud 7.

50 The foot member 4 has pipe sockets 9—9 opening into a chamber 11. Water is conducted from the city mains through pipes threaded into either one or both of the sockets 9—9 where the pump is employed in car washing or like service. The flanges 12—12 are formed on rearwardly extending arms 12' formed integral with the foot member 4 and projecting beyond the barrel 2. The flanges 12—12 are formed at right angles to the arms 12' so as to allow the pump to be mounted on a wall or other like foundation and with the barrel in spaced relation therewith, and they are preferably extended in parallelism with the inlets 9.

55 The inlet chamber 11 opens through an

annular valve port 13, suitable webs being provided to bridge the annular valve port 13. The foot member provides a double bead valve seat 14 for the inlet check valve 15 which preferably is an annular disk vertically slidable upon a cylindrical guide member 17, this guide member having a short threaded neck 18 threaded into a socket formed in the upper face of the foot member 4. The cylindrical guide member 17 is slotted to lighten the same and to prevent the deposit of sand and the like, and it has three spring seats 19 disposed about its periphery containing inlet check valve springs 20 tending to hold the check valve 15 upon its seat. The 30 springs may be omitted where only submergence pressure is depended upon to fill the pumping chamber.

The stud 7 which is threaded into a socket in the lower end of the discharge check valve 35 box 6, has a lock nut 22 for locking the stud in place. The upper end of the stud is recessed axially as by drilling, as indicated at 23, see Figs. 3 and 4, and this recess receives the lower end of a small tube or pipe 24 which extends down from the head member 1 through the water discharge pipe 5 and valve box 6, making a tight connection with the recess 23 by means of a packing ring 25, which is compressed between the wall of the socket in which the stud 7 is threaded and the end of the stud 7 about the tube 25. The upper end of the stud has an outer peripheral groove 26 which communicates through a drill hole 27 with the recess 23. The groove 26 in turn communicates with a horizontal passageway 28, preferably formed by drilling and plugging the casting of the valve box 6, and the horizontal passageway 26 in turn communicates with a vertical passageway 29 also preferably formed by drilling the casting.

A nipple 30 providing a raised annular valve seat 31 at its upper end is forced through a counterbore in the upper end of the drilled passageway 29. The valve seat 31 defines a valve port which is controlled by the low level controlled valve 32 having the yielding face 33 disposed in a recess in the outer arm of a lever 34. The lever 34 is pivoted intermediate its ends on a pin 35, which pin in turn is supported on a bracket member 36 providing two upturned ears or lugs in which the outer ends of the pin 35 rests. The yielding valve face 33 is held in a recess in the arm 37 by means of the screw plug 38 so that the same may be renewed if desired. A wire spring of the hair pin type, indicated at 39 in Fig. 1, has its ends connected as by screw 40 to the valve box 6 and by a screw 41 to the arm 42 of lever 34 respectively. The arm 42 of the lever 34 is Y-shaped reaching around the discharge pipe 5 and having an upturned end 43 adapted to be engaged by the traveling float 44 when the liquid in the pumping 130

chamber has reached a predetermined low level. The spring 39 tends at all times to close the valve 33, but when due to the lowering of water level on the expulsion stroke the 5 float 44 presses upon the end 43 of the lever 34, the valve is opened and the internal pressure in the chamber 3 causes liquid to be forced down through the valve passageway 29, lateral passageway 28, through drill hole 10 27, into recess 23 and thence on up through the tube 24 into a motor chamber 45 in the head member 1 for shifting the air control 15 valve, as will be described later.

The valve box 6 has a removable valve seat 15 member or plate 47, the flange of which is bolted to the box 6. An inwardly extending bead or valve seat 48 is adapted to be engaged by the discharge check valve 49, which comprises a metal back 50 and a yielding face 51 20 mounted upon a stem 52.

The valve member 49 is held on a reduced part of the stem, as by means of the nut 53. The forward end of the stem provides a guiding extension 54 mounted in a guide 55 supported by spider arms 56. The rear end of the 25 stem is guided in a hub or boss 57, which is drilled to provide a slight clearance between the stem 52 and the bore of the boss 57. The boss 57 has an extension at 58 containing a 30 threaded socket 59 for receiving the threaded end of the elbow 60. A removable orifice nipple 61 is seated in the end of the elbow 60 where it threads into the socket 59 to control the rate of water discharge through the 35 clearance space about the stem 57, as will be described later.

The upper arm of the elbow 60 is threaded to receive a threaded stud forming a part of the check valve housing 62, said check 40 valve housing containing a ball check valve 63 seating upon a seat 64 in the lower part of the housing to prevent inward flow of liquid towards the valve box 6 but permitting outward flow therefrom. The pin 66 prevents 45 the ball check valve 63 from seating over the end of the tube 67, which is held to the housing 62 by a threaded union 68. The tube 67 extends upwardly being carried up to the head member 1 and having its upper 50 end supported by a suitable sheet metal clamp 69, and the end of the tube directed into the lower end of the exhaust passageway 70. Tube 67 is however, smaller than the passageway 70 so that the latter is in communication 55 with the chamber 3, as well as with the tube 67.

The head member 1 comprises a head casting 72 having a flanged base 73 which cooperates with the upper end of the sleeve or barrel 2 defining the chamber 3, and this head casting is suitably cored and machined to provide the passageways and to be fitted with the various parts hereinafter described. The head casting 72 has a transverse passageway 85 suitably divided into various chambers and

passageways, and is provided with certain pipe sockets for the attachment of air admission and exhaust pipes and a water discharge pipe.

The exhaust connection is shown as a 70 threaded pipe socket 74, the air inlet connection is shown at 75 and the water discharge connection is not shown, although it will be understood that the same communicates with the cored passageway 76, which 75 communicates with the upper end of the water discharge pipe 5.

The air inlet connection 75 communicates by way of a cored passageway shown in dotted lines in Fig. 2, with the admission valve chamber 77 forming a part of the main transverse bore through the head casting 72. A removable plate 78 defines one wall of the air admission valve chamber and provides a 80 guide at 79 for the stem 80. The motor diaphragm or piston, which is in the shape of a flexible diaphragm, is shown at 71, and it has its margin clamped to the rim of the transverse bore through the head casting 72 by the motor chamber cap 81. The chamber 45 in the cap 81 has two connections, one connection indicated at the passageway 82 to a horizontal drilled passageway 83 leading to the central tube 24. The other connection is by way of a passageway 84 which 85 communicates with a drilled passageway 85 leading to the exhaust passageway 86.

The motor diaphragm 71 lies between the chamber 45 on one side and the chamber 87 on the other. The chamber 87 has two connections—one, a small leakage orifice 88 drilled through the plate 78 which separates the motor chamber 87 from the admission valve chamber 77. This orifice 88 permits the leakage of live air from the chamber 77 into the chamber 87. The other connection to the chamber 87 is a port 89 communicating by way of a passageway 90 with a valve 91.

The valve 91 comprises a ball check valve 92 adapted to seat over a port 93 formed in the valve seat member 94 bolted to the bottom of the head flange 73. The plate 94 has an integral bracket with a pivot pin 95 for the valve actuating lever 96, one arm of which, namely the shorter arm, has an operating pin 97 adapted to lift the ball 92 from its seat 93 when the float drops and the arm 98 loses its support from the float. The short arm likewise has a stop 99 adapted to engage the plate 94 to limit the motion of the pin 97.

The arm 98 embraces the water discharge pipe 5 and has an outer end portion 100, which is adapted to be engaged by the upper surface of the float 44 when water has substantially filled the pumping chamber on the filling stroke. A small diameter rod or wire 101 has an outwardly extending end 102 reaching over a pin 103 in the slotted end 100 125 130

of arm 98, and this rod 101 extends down to a point adjacent the low level control lever 34 where the rod encircles the discharge pipe 5, as shown at 104 in Fig. 3. The purpose of 5 the rod 101 is, as explained in the aforesaid Patent No. 1,658,032, to insure that the ball check valve 92 will be raised from its seat 93 at the end of the discharge stroke so that proper reversal of the valve mechanism may 10 be made. The valve mechanism 105 comprises an exhaust valve 106 housed in a chamber 107 which forms a part of the main transverse bore in the head 1, such chamber being closed on the outside by a screw plug 108 15 threaded into the head casting 72. The exhaust valve 106 comprises a metal back with a soft facing 109 adapted to engage the annular bead 110 which forms the seat for the exhaust valve 106.

20 The inlet valve 111 is adapted to seat upon the valve seat 112 which is formed as a shoulder in the bore of the head member 1. The valve 111 has an integral extending sleeve 113 which bears against the central part of 25 the face of the exhaust valve 106. The inlet valve 111 at its opposite end bears against a shoulder on the stem 80, and a threaded nut 114 on the end of the stem 80 holds the exhaust and inlet valves in spaced relation to 30 each other and solidly upon the stem 80. The inlet valve 111 has a loose sliding fit in the cylindrical guide 115 restricting the air flow sufficiently to provide a tendency for the admission valve to snap onto its seat.

35 The stem 80 is connected to the motor diaphragm 71 by a pair of clamping plates 116 and 117, which in turn are threaded upon the end of the stem 80 to secure these parts together. Movement of the diaphragm 71 is, 40 therefore, transmitted through the stem 80 to the air valve structure including the admission valve 111 and the exhaust valve 106.

45 The operation of the pump in service will now be described. Assuming that the parts are in the condition and position shown and that live air is connected at the connection 75, that exhaust connection 74 is open to atmosphere, that the discharge connection not shown is connected to the delivery passage- 50 way 76 and that connection to the city water mains is made at the pipe sockets 9-9 for supplying water to the pump: as the exhaust valve is open and the admission valve closed, live air does not reach the pumping chamber 55 in any appreciable quantity. However, live air from the chamber 77 passes through the orifice 88 into the motor chamber 87 from whence it escapes through the port 89, passage- 60 way 90 and past the valve 92 into the pumping chamber 3.

65 However, since the exhaust valve 106 is open, such air as escapes during the filling period passes out the exhaust connection. Water enters through the inlet chamber 11, 65 opens the inlet check valve 15 and fills the chamber. As the float 44 is lifted, it permits the low level control valve 33 to seat and close off the connection to the small central tube 24. This puts the motor chamber 45 in communication solely with exhaust 70 through the passageway 85, and the diaphragm 71 is therefore subjected to substantially atmospheric pressure on both sides. The pressure of live air against the admission valve 111 very definitely holds the valves 75 in the position shown in Fig. 2. As soon as the float 44 rises and lifts the arm 98 of the high level control lever 96, the check valve 92 seats upon its seat 93 and prevents the air which leaks through the orifice 88 80 from escaping into the pumping chamber and out the exhaust. The result is that the pressure flashes up in the motor chamber 45 to a value where the pressure of the same upon a relatively large area of the diaphragm 85 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

the float to the weight of the arm 98, and thereby opening the valve 92.

While air is admitted past the valve 111 through the clearance between the valve and its guide 115, the discharge check valve 49 in the valve box 6 is open, permitting water to flow out by way of the discharge pipe 5 to the closed or pressure delivery system. During this time the control check valve 63 is seated as shown in Fig. 1 to prevent air under pressure passing down through the tube 67 and into the discharge valve box 6. When the float 44 has been carried to low level by the expulsion of water and has opened the pilot valve 33 to control operation of the motor for shifting the valve structure 105 to exhaust position, the pressure of the compressed air in the pumping chamber 3 drops very rapidly due to the large exhaust 20 valve opening.

The valve has only a small lift, but has a fairly large diameter so that a considerable opening is presented. The pressure of the air quickly drops below the pressure of the 25 water retained in the valve box 6 and in the discharge system with the result that water pressure in the box 6 exceeds the pressure of air in the pumping chamber 3, with the result that water is expelled past the check valve 20 63 through the tube 67 into the central chamber between the admission and exhaust valves 111 and 106 respectively.

This flow of water preferably continues during the filling stroke in order to insure 35 sufficient transfer of heat to the metal walls which are filled by the rapid expansion of air at the exhaust valve 106. Obviously, if desired, the rate at which water is driven out of valve box 6, that is, from the discharge 40 system which is under pressure beyond the check valve 50, may be controlled by the substitution of an orifice nipple 61 of the right size in the elbow 60.

Attention is called to the fact that the guide 45 of the discharge check valve stem 52 in the hub 57 is peculiarly subject to interference with any sand or deposit which may be carried in with the water. By drawing the water for heating the exhaust valve and chamber from the clearance space about the stem 52 provides the normal function of washing out this clearance space, thereby to expel any foreign matter which might become lodged in the same.

55 If desired the check valve 63 may travel from its lower seat where it prevents the ingress of air into the valve box 6 to an opposed seat at the end of the tube 67 where it would limit further flow outwardly of water. In 60 other words, the amount of water then would be controlled by the time that it took the water to raise the check valve from its lower seat to its upper seat and only a very short squirt of water would be delivered into the 65 passageway 70.

Obviously water may be taken from anywhere in the discharge system above the check valve 50 or in fact might be taken from any other part of the pump or system for washing or spraying the exhaust valve and its adjacent part with a liquid to prevent frosting or freezing. It is to be observed that the expansion of the air at the admission valve on admission of live air to the pumping chamber tends also to cool the metal of the head 70 because there is a certain wire drawing between the admission valve 111 and its guide 115, such wire drawing being useful to assist in propelling the admission valve to its seat when the exhaust valve 106 is forced away 75 from its seat.

It will be seen, therefore, that even though the pump is subjected to continuous operation at heavy duty, the continued expansion of air in entering and leaving the pumping 80 chamber will be prevented from frosting or freezing the valves and adjacent parts because of the continued feeding of the same by discharging water upon or into the vicinity of the same. It will be apparent that the latter 85 part of the exhaust stroke where air at a pressure less than the pressure prevailing in the valve box 6 flows out through the passageway 70 and past the exhaust valve, this will carry with it the water which is discharged by the 90 pipe 67 and thus keep the metal parts warm enough to prevent the deposit of frost 95 or ice. I believe it is broadly new to make provision for passing water out the discharge pipe of a pneumatic pump for defrosting the 100 same.

I do not intend to be limited to the details shown and described.

I claim:

1. In a pneumatic displacement pump having an air discharge passage, the method of preventing the deposit of frost adjacent the air discharge passage of said pump which comprises passing water through said air discharge passage.

2. The method of preventing frosting of the exhaust valve of a pneumatic pump which comprises spraying the exhaust valve with a small quantity of the liquid to be pumped for each operation of the valve.

3. The method of preventing frosting of the exhaust valve of a pneumatic pump which consists in carrying a small amount of water out through the valve with the exhausted air.

4. The method of preventing freezing of the exhaust valve of a pneumatic pump which consists in spraying the inside of the valve with cold water.

5. The method of preventing frosting of the exhaust valve of a pneumatic pump which comprises driving water from the pumping chamber by pneumatic pressure to place it under a yielding pressure head, opening the exhaust valve to release the pneu-

matic pressure, closing off communication between the discharged water and the compressed air, permitting the escape of a small quantity of water under pressure and projecting the same upon the exhaust valve when the pressure of the water on the discharge side exceeds pressure of the escaping air.

6. In a pneumatic pump having a pumping chamber and a pneumatic exhaust valve, a discharge conduit, a discharge check valve therefor, means for opening the exhaust valve after a charge of liquid has been expelled from the pumping chamber and a discharge connection for discharging liquid from the discharge conduit through the exhaust valve to prevent frosting of the same.

7. In a pneumatic pump having a discharge pipe, a discharge check valve for said pipe, an air exhaust valve, the combination of a tube leading from said discharge pipe above the check valve and directed to discharge the fluid therein into heat exchange relation with said exhaust valve.

8. In a pneumatic pump having a discharge pipe, a discharge check valve for said pipe, and an air exhaust valve, the combination of a tube leading from the discharge pipe above the check valve and directed towards said exhaust valve, and a check valve preventing the flow of air into said discharge pipe.

9. In a pneumatic pump, the combination of a discharge pipe, a discharge check valve box having a check valve for said pipe, a pneumatic exhaust valve, a tube extending from said valve box and directed towards the exhaust valve, and a check valve controlling said tube.

10. In a pneumatic pump, the combination of a discharge pipe, a discharge check valve box having a check valve for said pipe, a pneumatic exhaust valve, a tube extending from said valve box and directed towards the exhaust valve, and a check valve controlling said tube, said check valve comprising a valve housing having a valve seat and a ball valve therein adapted to open when pressure in the discharge pipe exceeds the pneumatic pressure in the pumping chamber.

11. In a pneumatic pump, the combination of a pumping chamber, air control valve means for said chamber and including an air exhaust valve, a discharge pipe, a liquid discharge valve box at the lower end of said pipe having a discharge check valve, means including a float guided on the pipe for controlling the opening of the exhaust valve upon predetermined low level of liquid in the chamber, a tube extending from said box towards the exhaust valve and adapted to discharge liquid towards the exhaust valve when the exhaust valve is opened.

12. In a pneumatic pump having a pump-

ing chamber and an air exhaust valve, the combination of means for opening the valve upon low level of liquid in the pumping chamber, and means for injecting a small quantity of water into the air escaping past the exhaust valve for each operation of said exhaust valve.

13. In a pneumatic pump, the combination of a pumping chamber, an air exhaust valve for the pumping chamber, means for opening said exhaust valve when liquid has been expelled from the pumping chamber, and means within the pumping chamber for spraying water upon the exhaust valve to prevent frosting of the same.

14. In a pneumatic pump, the combination of a pumping chamber, an air exhaust valve for the pumping chamber, means for opening said exhaust valve when liquid has been expelled from the pumping chamber, a liquid discharge check valve having a stem, a guide for the stem providing an annular clearance space, means providing a discharge passageway leading from said clearance space to the exhaust valve for cleaning this space and for discharging liquid onto the exhaust valve to prevent frosting of the same.

15. In a pneumatic pump having a pumping chamber, a discharge pipe, a discharge check valve having a stem, a guide for the stem providing an annular clearance space, and a tube leading from the end of said guide to convey particles out of said clearance space.

16. In a pneumatic pump having a pumping chamber, a discharge pipe, a discharge check valve having a stem, a guide for the stem providing an annular clearance space, a tube leading from the end of said guide to convey particles out of said clearance space, and a valve for limiting the flow of liquid through said tube in one direction.

17. The method of preventing the deposit of frost near the air valves of a pneumatic displacement pump having passages adjacent said valves which comprises passing water through the passages so as to subject said valves to the latent heat of the water.

18. The method of preventing the deposit of frost in a gas expansion pump having gas discharge passages, which method comprises passing some of the pumped fluid in thermal contact with the gas passages.

19. In a gas expansion instrumentality for pumping liquids and having a valve and valve passage, the method of preventing the deposit of frost near the valve which comprises bringing some of the liquid into contact with the passage adjacent said valve.

20. In a structure employing a gas discharge valve and a passage adjacent, the method of effecting a change of temperature of the valve which comprises directing a mass of liquid into the interior of said passage in thermal relation with the valve.

21. In a structure employing a gas discharge valve and a passage adjacent, the method of preventing the formation of frost near the valve due to expansion of the gas which comprises directing a flow of fluid in
5 the interior of said passage in thermal relation with the valve.

22. In a structure employing a gas discharge valve and a passage adjacent, the method of preventing the formation of frost near the valve due to expansion of the gas which comprises directing a flow of liquid in
10 the interior of said passage in thermal relation with the valve whereby the valve and
15 passage are subjected to the latent heat of fusion of the liquid.

In witness whereof I hereunto subscribe
my name this 19th day of July, 1928.
